UNITED STATES PATENT OFFICE.

EDGAR H. FREEMAN, OF TRENTON, NEW JERSEY.

LAMP-SOCKET FIXTURE.

1,207,156.

Specification of Letters Patent.

Patented Dec. 5, 1916.

Application filed June 29, 1915. Serial No. 37,058.

To all whom it may concern:

Be it known that I, EDGAR H. FREEMAN, a citizen of the United States, residing at Trenton, in the county of Mercer and State 5 of New Jersey, have invented certain new and useful Improvements in Lamp-Socket Fixtures, of which the following is a specification.

This invention relates to electrical lamp 10 sockets, and more particularly to means for securing the same to the end of a supporting fixture.

The use of lamp sockets in connection 15 with a socket cover, or what is more commonly known as a husk fitting, makes it necessary to securely and rigidly hold the cap of the socket to the fixture, so that the shell may be readily locked to the cap and the entire socket prevented from turning 20 with the screwing in and out of the lamp.

To this end, the invention has generally in view novel and improved means whereby the attachment of the socket to the fixture may be greatly facilitated, as well as 25 adjustments and repairs.

The principal object of the invention is to provide a common fastening device which is capable of locking the cap to the fixture member, and also positively locking the 30 socket cover against rotation. Ordinarily, the socket cover is merely frictionally held in position, by being clamped between the locking member carried by the cap and the end of the fixture, but according to the present invention, it is contemplated to positively engage and lock the socket cover with 35 the cap and fixture nipple.

A further object is to provide simple and substantial means whereby a secure and 40 positive union is obtained, thus forming a rigid and efficient structure.

In this connection, the invention also has in view utilization of relatively few and inexpensive parts, that materially enhance 45 the commercial, as well as the practical aspect of the invention.

With the above and other objects in view which will more readily appear as the nature 50 of the invention is better understood, the same consists in the novel construction, combination and arrangement of parts hereinafter more fully described, illustrated and claimed.

A preferred and practical embodiment of 55 the invention is illustrated in the accompanying drawings in which—

Figure 1 is an enlarged vertical sectional view of a socket cover and socket cap secured to the end of a fixture according to the present invention. Fig. 2 is a perspective view of the socket cap shown in Fig. 1. Fig. 3 is a bottom plan view of the socket cap.

Similar reference characters designate corresponding parts throughout the several 65 figures of the drawings.

In carrying out the present invention, it is proposed to utilize a socket cap 1 of any design which may be connected in any well known manner with the socket shell carrying the usual switch mechanism within. By reference to the drawings, it will be observed that this socket cap 1 carries therewith a separate nut member 2 which is rigidly fitted in the top thereof. This nut 70 member includes a clamping head portion 3 projecting above the socket cap, and also a substantial body portion 4 extending inside of the cap and having its end face formed into an angular tool receiving seat 5. The said nut member 2 is further provided with a central threaded opening 6 having on each side thereof, preferably at diametrically opposite points, relatively small threaded openings 7 which are adapted 75 to receive hard steel locking screws 8. As can be best observed from Fig. 1, each of these locking screws essentially comprises a threaded body having one end provided with the usual slot 9 for receiving a screw 80 driver or similar tool, while the opposite end is formed into a pointed piercing cone 10. Since the nut member 2 is rigidly carried by the socket cap 1, the nut and cap 85 may be handled as a single unit, thus greatly facilitating the fitting of the cap to the pipe fixture. As shown in Fig. 1 this fixture nozzle is designated in its entirety by the reference 11, and includes a threaded extension 12 for receiving the nut member 2 and an annular flange 13 whose under face presents a rigid anvil or abutment shoulder for the nut on the cap 1 to work against. By further reference to Fig. 1, it will be apparent that the cap carrying 100 the nut member 2 may be readily screwed onto the threaded extension 12 of the fixture nozzle by means of a suitable tool engaging within the wrench seat 5, to thus clamp the edge 14 of the socket cover or 105 husk fitting 15 between the head 3 of the nut and the abutment on the nozzle.

While the nut may be screwed onto the fixture nozzle so that all of the parts may be frictionally locked and held against rotation, it is the purpose of the screws 8 to positively engage and hold all of the parts so that none of them can turn. That is to say, after the nut 2 carried by the cap has clamped the cover 15 in position, the screws 8 are turned so that the piercing points 10 thereof penetrate and puncture the edge 14 of the cover to produce metal burs that are forced or embedded in the anvil face of the abutment shoulder presented by the flange 13. Thus, the nut, cap, and cover are all positively locked together by means which is accessible from within the socket cap.

From the foregoing, it is thought that the many features and advantages will be readily apparent without further description, and it will also be understood that changes in the form, proportion and minor details of construction may be resorted to without departing from the spirit of the invention or scope of the appended claims.

25 I claim:

1. A lamp socket mounting, including in combination, a fixture member, a socket cap having a fixture engaging portion, a socket cover having a portion thereof interposed 30 between the fixture member and the fixture engaging portion of the cap, and locking elements movable in and through the fixture engaging portion of the cap to lock the cap and cover to the fixture member.

35 2. A lamp socket mounting, including in combination, a fixture member, a socket cap having a fixture engaging portion, a socket cover having a portion thereof interposed between the fixture member and the fixture 40 engaging portion of the cap, and locking elements movable in and through the fixture engaging portion of the cap in a plane substantially parallel to the longitudinal axis of the fixture member to lock the cap and cover thereto.

45 3. A lamp socket mounting, including in combination, a fixture member, a socket cap having a fixture engaging portion, a socket cover having a portion thereof interposed 50 between the fixture member and the fixture engaging portion of the cap, and separate removable locking elements carried by and projecting through the fixture engaging

portion of the cap to lock the cap and cover to the fixture member, said separate removable locking elements being accessible from the interior of the socket cap. 55

4. A lamp socket mounting, including in combination, a fixture member, a socket cap carrying therewith a nut member engaging 60 the fixture member, a socket cover having a portion thereof interposed between the nut and fixture member, and locking elements projecting longitudinally through said nut member and arranged to force said cover 65 into positive locking engagement with the fixture member and also secure the cap against rotary movement.

5. A lamp socket mounting, including in combination, a fixture member, a socket cap 70 having means rigid therewith for detachably engaging the fixture member, a socket cover, and a fastener carried by said means for forcing said cover into positive engagement with the fixture member, and to secure 75 the cap against rotary movement.

6. A lamp socket mounting, including in combination, a fixture member, a socket cap, a nut member rigidly carried by said cap and detachably engaging said fixture member, 80 a socket cover, and pointed screws carried by said nut member and adapted to lock the same and said cover to the fixture member.

7. A lamp socket mounting, including in 85 combination, a fixture member having a threaded nipple extension and an annular abutment shoulder, a socket cap, a nut member rigidly carried by said cap and having a central threaded opening for engaging the 90 nipple extension of the fixture member, said nut member having a head portion projecting above the cap and a body portion extending within the cap to form tool engaging means, a socket cover adapted to be 95 clamped between the head of the nut member and the abutment shoulder on the fixture member, and means carried by said nut member for positively locking the cap and cover to the fixture member. 100

In testimony whereof I hereunto affix my signature in the presence of two witnesses.

EDGAR H. FREEMAN.
